UNITED STATES PATENT OFFICE

123,815

DESIGN FOR A COMBINED ROCKING BLOTTER AND STAMP MOISTENER

Harry O. Mitchell and Ludwig Oppenheimer,
Denver, Colo.

Application April 15, 1940, Serial No. 91,685

Term of patent 3½ years

To all whom it may concern:

Be it known that we, Harry O. Mitchell, a citizen of the United States of America, and Ludwig Oppenheimer, a citizen of Germany, both residing at Denver, in the county of Denver and State of Colorado, have invented a new, original, and ornamental Design for a Combined Rocking Blotter and Stamp Moistener, of which the following is a specification, reference being had to the accompanying drawing, forming part thereof.

In the drawing:

Fig. 1 is a perspective view of a combined rocking blotter and stamp moistener showing our new design.

Fig. 2 is a plan view thereof.

We claim:

The ornamental design for a combined rocking blotter and stamp moistener, as shown.

HARRY O. MITCHELL.
LUDWIG OPPENHEIMER.
